UNITED STATES PATENT OFFICE.

PERCY H. THOMAS, OF EAST ORANGE, NEW JERSEY, ASSIGNOR TO COOPER HEWITT
ELECTRIC COMPANY, OF NEW YORK, N. Y., A CORPORATION OF NEW YORK.

METHOD OF REMOVING DELETERIOUS GASES.

981,497.

Specification of Letters Patent. Patented Jan. 10, 1911.

Application filed January 23, 1904. Serial No. 190,284.

To all whom it may concern.

Be it known that I, PERCY H. THOMAS, a citizen of the United States, and resident of East Orange, county of Essex, State of New Jersey, have invented certain new and useful Improvements in Methods of Removing Deleterious Gases, of which the following is a specification.

The idea of obtaining a high degree of vacuum without the use of an external pump which is itself capable of exhausting a given chamber or receptacle to the required degree, has been disclosed by me in an application, Serial Number 190,283, filed January 23, 1904. In the said application, I show and describe means whereby vapors or gases may be caused to pass through a chamber and carry with them the noxious or injurious gases which it is desired to remove from the chamber, and I also provide means for sealing off the chamber while the process of expulsion is still going on. The means for expelling the vapors, as set forth in the other application referred to, are represented as sources of heat, which, acting on the external wall of the chamber, vaporize a volatile substance inside of the chamber and through the force of expansion cause the said vapors to pass through an exit tube which is afterward sealed off. Chemical or other means for producing and expelling the vapors may be employed.

The present invention is generally similar to that above referred to, but instead of relying upon the expelling power of heat or of chemical or other means alone for causing the vapors to pass out through the exit tube and thus remove the deleterious gases from the chamber, I provide a mechanical vacuum pump at the remote end of the exit tube, for assisting in the withdrawal of the vapors and gases.

The invention is illustrated in the accompanying drawing which is an elevation and part section of an apparatus adapted to secure the objects of this invention.

In the drawing I have represented as the body from which it is desired to remove injurious gases, a tube 1 supplied with mercury electrodes, 2 and 5, the whole constituting one form of a well-known gas or vapor electric apparatus. The tube 1 is supplied with enlargements, 4 and 3, which serve as condensing chambers. In the present instance I represent both elec-

trodes as being formed of mercury, but one of them may be of some solid material, such as iron. To one end of the apparatus, I connect an exit tube, 6, with which is connected a mechanical pump, 7, of any preferred type. Around the apparatus to be exhausted I place a heat retaining shield, 8, and underneath the apparatus I locate a jet of flame, or other source of heat, 9.

The operation of freeing the chamber 1 from injurious gases consists in lighting the jet 9 and applying a high degree of heat to the container 1 throughout its length thereby vaporizing some of the mercury of the electrode 5. At the same time I may apply suction to the remote end of the tube 6 through the medium of the pump 7, thereby assisting the natural tendency of the vapor to pass out through the tube 6 under the influence of the heat applied as described.

I have found in practice that while the pump 7 could not of itself be relied upon to produce a sufficiently high vacuum in the chamber 1, yet such a pump combined with the application of heat to the tube or container will produce a very high degree of vacuum with a considerably smaller application of heat, it being understood that the tube 6 is sealed off, however, while the forces tending to expel or withdraw the vapors from the tube are at work. The economy in the application of heat is not only desirable in itself, but may constitute an important factor in the operation when the container is of such a character or composition as would make it likely to be injured or destroyed by the application of excessive heat.

When the removal of noxious gases or vapors is accomplished by the process herein described, it is possible to so proportion the amount of work done by the pumping apparatus and by the application of heat as to secure the best economy of operation.

In describing the pumping apparatus as a mechanical pump, I wish to exclude the use of a mercury pump which in itself might be sufficient to secure any desired degree of vacuum in the container.

Instead of causing the vaporization of a liquid by heat and the expulsion of a portion of the vapor by the same means, I may employ chemical or other means for producing a vapor and expelling a portion thereof.

The narrow throat 10 serves a critical

function in the operation of the device described herein, inasmuch as it reduces the cross-section of the passage through which the vapor of mercury or other vapor utilized 5 to expel the deleterious gases inclosed within the chamber pass. This reduction of the cross-section serves to increase the velocity of the expelling gases or vapors until it exceeds that of the diffusion of any of the deleterious gases on the pump side of the apparatus. When the exhaustion is complete or carried to a satisfactory limit, the apparatus may be sealed off at any point not nearer to the pump than the narrow 10 throat 10.

It is well known that certain chemical processes which can be excited by suitable means produce large volumes of gases or vapors. Gases or vapors formed by such a chemical 20 process may be utilized in place of the vapor produced from the mercury within the chamber by heat to secure exhaustion and when the process is sufficiently complete the chemical production of gases may be discontinued 25 by the suppression of the exciting means.

In applicant's companion cases Serial Number 190,283, filed January 23rd, 1904, and Serial Number 265,503, filed June 16th, 1905 as well as in applicant's patents 806,853 30 issued December 12th, 1905 and No. 845,670 issued February 26th, 1907 are made claims covering related subject matter to that claimed herein.

I claim as my invention:—

35 1. In a vapor electric apparatus, a container having a suitable exit passage provided with a narrow throat, and an exhaust tube, a volatilizable fluid therein, external means for partially removing the pressure in 40 the exhaust tube and for removing products delivered to said exhaust tube, means for vaporizing a portion of such fluid and causing the produced vapor to pass rapidly through the container and means for sealing 45 off said container before the cessation of the rapid passage of vapor through said narrow throat.

2. A vapor electric apparatus including a container provided with an exit tube having 50 a discharge outlet, means for producing a vapor in said container, and causing it to pass rapidly through the container with a velocity greater than the diffusing velocity of discharge gases, means for partially reducing the pressure in the discharge outlet 55 and for removing vapors appearing at said outlet, and a narrow throat in said tube

nearer the container than the discharge outlet, adapted for sealing off during the exhaustion of said vapor at said velocity. 60

3. The combination with a hermetically sealed apparatus including a container having an exhaust tube with a constricted throat and a discharge portion, of a body of mercury within said container, a heat jacket surrounding said container, means for producing heat and vaporizing a portion of said mercury, a mechanical air pump adapted to partially remove the air and other gases and vapors in said discharge portion, means for 70 producing a velocity of vapor in said restricted throat superior to the maximum rate of diffusion of the gases in the exhausted portion and means for sealing off the container during the maintenance of such velocity at a point no further remote from the container than said narrow throat. 75

4. The method of manufacture of vacuum vapor apparatus containing a volatilizable liquid and requiring a high degree of purity 80 of vapor, which consists in connecting the interior of the apparatus to an exhaust chamber, reducing the pressure in the exhaust chamber below atmospheric pressure but above the final pressure of exhaustion 85 for the apparatus, vaporizing a portion of the liquid within the apparatus to wash out the foreign gases within the chamber into the exhaust chamber, maintaining a velocity of vapor discharge greater than the diffusion 90 rate backward of foreign gases and sealing off the container upon the securing of the proper degree of purity therein while maintaining the discharge vapor velocity above 95 the critical value. 100

5. The method of exhausting a vessel containing volatilizable material, which consists in driving foreign gases from the vessel by the convective action of vapor raised to an abnormally high pressure within the chamber, preventing the return of said dispelled gases by the maintenance of a superior internal pressure and outward velocity of vapor from the chamber, and closing the chamber during the maintenance of the abnormal pressure, and the outward velocity of the vapor. 105

Signed at New York, in the county of New York and State of New York, this 11th day of January, A. D. 1904.
